UNITED STATES PATENT OFFICE.

GEORGE W. HALLOCK, OF NEW YORK, N. Y., ASSIGNOR TO THE SAFETY CAR HEATING & LIGHTING COMPANY, A CORPORATION OF NEW JERSEY.

ELECTRICAL SYSTEM.

1,143,191.

Specification of Letters Patent. Patented June 15, 1915.

Application filed December 7, 1909. Serial No. 531,759.

To all whom it may concern:

Be it known that I, GEORGE W. HALLOCK, a citizen of the United States, residing in the borough of Brooklyn, county of Kings, city and State of New York, have invented new and useful Improvements in Electrical Systems, of which the following is a description.

My invention pertains to that class of 10 electrical systems in which it is desired to charge a storage battery and operate lamps or other translating devices from a generator driven at variable speeds.

My invention has for its particular object 15 to provide means whereby various automatic devices used to perform certain functions in systems of this character may be designed and operated so as to meet certain practical working conditions, particularly to 20 be met with in the lighting of railway cars by electricity generated by a dynamo driven from the car axle.

As my invention is largely used for this 25 purpose it will be described in connection with a car lighting system in which it is embodied.

The drawing is a diagram of one type of 30 system of electrical distribution comprehending my invention.

In the drawing 1 represents a dynamo or 35 generator driven from a variable source of motion as from the axle of a car, it being understood, of course, that the dynamo indicated is so arranged as to deliver current of constant polarity regardless of reversals in direction of motion of the car. From the positive brush of the generator the lead 2 is carried to the winding 3 and thence to the switch terminal or contact member 4 adapted to coöperate with the switch member 5 in a manner which will be hereinafter described.

6 represents a shunt coil connected with the lead 2 as by wire 7 and with the negative terminal of the generator as by wire 8. The coils 3 and 6 are wound in such manner as to assist each other when current is flowing from the generator through the lead 2 and are wound in such position with respect 50 to the core 9 as to tend to lift the same when excited in such manner as to cause the contact member 5 to establish electrical connection between the member 4 and the member 10. The member 4 is provided with a car-

bon contact piece 11 and the member 10 with 55 a like carbon contact piece 12.

13 and 14 represent similar carbon contact pieces carried upon the flexible spring 15 electrically connected with the member 5.

16 represents any suitable type of stop 60 limiting the downward movement of the core 9 when the coils are deenergized.

17 represents a conducting member pivotally mounted as shown at 18 and adapted to 65 normally tend to establish electrical connection with the member 19. From the contact member 10 the main 20 is carried to the resistance 23 from which the main 24 is led through switch 57 to the lamps or other 70 translating devices indicated at 25 from which return is made to the generator by lead 26. The main 20 has connected therewith the wire 27 which leads to the coil 28, from which the wire 22 is carried to wire 75 29 and then to the lever 17 coöperating with the contact member 19 from which the wire 21 is led to a point upon the main 24 between the resistance 23 and the switch 57. The wire 29 is led to the positive side of the 80 storage batteries 30, the negative side of which is connected as by wire 31 with the lead 26. The coil 28 surrounds the core 32 supported by the bell-crank lever 33 pivoted as at 34 and carrying the member 35 which 85 in turn carries the conducting yoke 36 insulated therefrom as by member 37 and counterbalanced as by means of weight 38. The adjustable spring 39 tends to draw the yoke 36 against the carbon resistances 40 so as 90 to compact and reduce the resistance thereof and it will be evident that pull upon the core 32 caused by the excitation of the coil 28 will thus tend to decrease the pressure upon the carbon disks 40 in such manner as 95 to increase the resistance thereof. The wire 41 is carried from the lead 2 to one side of the carbon disks 40 from the other side of which the wire 42 is carried to one side of the field winding 43, the other side of which 100 is connected with the negative pole of the generator as by wire 44. The coil 45 also surrounds the core 32 and has one of its ends connected to the wire 46 leading to the contact 47.

48 represents a pivotally mounted armature normally drawn in a downward direction by the adjustable spring 49.

60

80

90

100

105

50 is a wire connecting the wire 41 with one end of the winding 51 the other end of which is connected by wire 52 with the lead 26. The coil 51 is provided with the core 53 which when excited by current in the coil 51 tends to attract the armature 48 and cause electrical contact between the same and contact member 47, thus establishing connection between the wire 50 and the wire 46 through the wire 56, armature 48 and contact 47. The coil 45 has its other terminal connected with the wire 54 which is connected to the lead 26 through the adjustable resistance 55. The windings 28 and 45 are so arranged that current flowing from the generator to the storage battery through the coil 28 tends to cause a downward pull upon the core 32 so as to increase the resistance 40; and current flowing from the lead 2 to the lead 26 through the coil 45 when the circuit is closed at 47 tends to assist the said coil 28 in the above outlined operation.

The practical operation of my improved system is substantially as follows starting with the generator at rest and with no lamps or translating devices in circuit: Under these conditions the core 9 of the main switch will be entirely released and the switch will be wide open and resting upon the pin 16. The lever 17 will then be in the position shown in the drawing and in contact with the member 19 so that if the lamp switch 57 be closed current flowing from the battery to the lamps will mostly pass through wire 29, wire 22, lever 17, wire 21, switch 57 and wire 24 and return through lead 26 and wire 31 to the battery. A small current will also flow from wire 29 through coil 28 and wire 27, main 20 and resistance 23 to the lamps but owing to the resistance of this circuit the current therein will not be sufficient to cause any appreciable effect upon the core 32. With the generator at rest and the main switch open as above described the coil 51 will not be energized and the spring 49 will pull the armature 48 away from the contact 47 and break the circuit therethrough and there will be no current flowing in the coil 45. If the generator now be started current will flow through lead 2, wire 41, resistances 40, wire 42, field coil 43 and wire 44 back to the generator causing the field to build up in a well-known manner. Current will also flow from wire 7 through coil 6 and return to the generator through wire 8. When the generator voltage is substantially that of the normal voltage of the battery 30 the coil 6 will cause the core 9 to be lifted into the position shown in the drawing which will cause contact between the members 11 and 13 and 12 and 14. As these are carbon contacts the resistance across the same will depend upon the pressure exerted by the

tendency of the core 9 to rise and bend the spring member 15 and the current flowing through the coil 3 across the contacts 11 and 13 through spring member 15 and across contacts 12 and 14 will tend to cause the core 9 to be raised against the spring action of the member 15 so as to complete the circuit through the contact member 5 of very low or negligible resistance. If the voltage of the generator be sufficient that considerable current shall flow to the battery the coil 3 will cause the circuit to be closed through the member 5 immediately and the contact between 17 and 19 to be simultaneously broken. The breaking of this contact will throw the resistance 23 in circuit with the lamps or translating devices in such manner as to compensate for the increase in generator voltage above that of the battery upon which they may have been operating before. I now adjust the spring 39 so that the current flowing to the battery through the coil 28 will not appreciably increase the resistance of the carbon disks 40 until a predetermined current shall be delivered to the battery when any further increase in current will cause the core 32 to be drawn downward and resistance inserted in the field circuit in such manner as to hold the current supplied to the battery practically constant. If now the generator continues to deliver its maximum current to the batteries they will in course of time become charged until their voltage shall rise appreciably and cause the current flowing in the coil 51 to be materially increased. As it is not desired to continue this maximum charging after the batteries have become charged so that their voltage shall have risen to a predetermined point I so adjust the spring 49 that when this voltage be reached the coil 51 will cause the armature 48 to be raised and cause contact to be made with the member 47 and thus allow current to flow from the generator through wire 41, wire 50, wire 56, armature 48, contact 47, wire 46, coil 45, wire 54 and adjustable resistance 55 to the lead 26. I now adjust the current in the coil 45 by means of the adjustable resistance 55 so that the said coil acting upon the core 32 serves to increase the resistances 40 sufficiently to cause the generator voltage to drop to nearly that of the battery—that is, I so adjust the current in the coil 45 that a very small current flowing in the coil 28 is sufficient to cause insertion of resistances 40 and prevent any further rise in voltage of the generator regardless of increases in speed. I now so arrange the main switch that when this small current is flowing through the coil 28 the core 9 will drop to the position shown in the drawing breaking connection between the members 4 and 10 and leaving only a comparatively high re- 130

sistance connection across the mains between contacts 11 and 13 and 12 and 14. This action of the switch will also cause the lever 17 to make contact with 19 so that 5 the battery may supply part of the current to the lamps or translating devices if the switch 57 be closed inasmuch as the resistance of the circuit from the battery through member 17, contact 19 and wire 21 is much 10 less than that from the generator to the battery through resistance 23. If now the generator shall stop the contacts between the members 11 and 13 and 12 and 14 will be open and the armature 48 will drop 15 and break the connection at 47 throwing the coil 45 out of circuit and any current which may be used for lighting the lamps will be taken directly from the battery as hereinbefore described. Upon starting 20 again, if the battery voltage still remain sufficiently high the main switch in the first step of its operation, to wit: closing the contacts 11 and 13 and 12 and 14, will cause the coil 51 to immediately close the contact 25 at 47 and thus cut in the coil 45 in the manner above described so that upon further rise in speed of the generator a slight current flowing through the carbon contacts of the switch and thence through the coil 28 will 30 be sufficient to so operate the resistances 40 that further increase in current will not take place and there will not be sufficient current in the coil 3 to cause the core 9 to be further raised than shown in the drawing 35 and the small maximum voltage current only will be supplied to the battery. However, if there be sufficient lamps or translating devices thrown on as to require considerable current, the current then flowing through the coil 3 will cause the core 40 9 to be raised and the circuit completed through the member 5 and then the generator will supply the current to the translating devices through resistance 23 and 45 the small charging current to the battery. If, however, for any reason, as for instance, by the operation of the lamps or translating devices, the voltage of the batteries has been lowered during the stoppage of the generator 50 the coil 51 will not cause the contact to be made at 47 and the coil 45 will not be energized and the full charging current will necessarily flow through the coil 28 before resistances will be inserted in the field which will allow the coil 3 to lift the core 9 in such manner as to complete the circuit through the member 5 and break the contact at 19 and throw the resistance 23 in the lamps or translation circuit. 55 From the foregoing it will be obvious that I have produced a simple system of electrical distribution in which a variable speed generator may be caused to charge a storage battery until its voltage shall have 60 reached a certain predetermined amount

and then automatically cut down the charging current until the same is of very small value without altogether cutting out the generator. Also that in my system if any appreciable load be thrown on the translation circuit the generator will carry the same and still supply only a small current to the batteries when this is desirable as above outlined. 70

I do not wish in any way to limit myself 75 to the exact construction shown in the drawing nor to the exact description of any particular mode of operation which I have given in explanation of one type of system embodying the essentials of my invention 80 which is as set forth in the following claims.

I claim—

1. An electric system comprehending a generator, a storage battery, lamps or translating devices, a regulator for the generator 85 responsive to current fluctuations, means cooperating therewith in the regulation of the generator responsive to voltage fluctuations and an automatic switch controlling the generator circuit including a resistance determined by the above named regulating 90 means in the regulation of the generator.

2. An electric system comprehending a generator, a storage battery, and translating devices, combined with means for regulating the generator responsive to variations in current; means for varying the action thereof; means for controlling the latter means dependent upon the voltage of the battery, and a main switch operated 95 upon variations of the generator and variably controlling the generator current.

3. An electric system comprehending a generator, a storage battery and translating devices combined with means for regulating 105 the generator responsive to variations in current, means for varying the action thereof dependent upon the voltage of the battery and a main switch controlling the generator circuit affected by the action of said 110 voltage operative means to increase the resistance of the generator circuit a finite amount by the action thereof.

4. An electric system comprehending a generator, a storage battery and translating devices combined with means for regulating the generator responsive to variations in current, means for varying the action thereof dependent upon the voltage of the battery and a main switch controlling the generator circuit affected by the action of said 115 voltage operated means to increase the resistance of the generator circuit by the action thereof and means whereby said switch assists in the control of current in 120 the translation devices.

5. An electric system comprehending a generator, a storage battery and translation devices, an electromagnetic switch controlling the generator circuit, a regulator for 130

the generator, means for affecting said regulator upon rises in voltage in such manner as to operate the main switch and means whereby said operation increases the resistance in the generator circuit a finite amount.

6. The combination with a generator, a main switch controlling the circuit thereof, a storage battery charged thereby, lamps or translating devices and means for controlling the generator, whereby the said controlling means affects the main switch to adjust the resistance of the main circuit.

7. The combination with a generator, a main switch controlling the circuit thereof, a storage battery charged thereby, lamps or translating devices and means for controlling the generator, whereby the said controlling means affects the main switch to vary the resistance of the main circuit a finite amount and means operated by said main switch for controlling the resistance in the translation circuit.

8. An electric system comprehending a generator and a battery; and a work-circuit to be operated thereby; a generator regulator; and means whereby the effect produced by said regulator will automatically oppose resistance to the action of the generator a finite amount and directly control the operative relation of the battery to the work circuit.

9. An electric system comprehending a generator and its circuit; a field-circuit; a battery and its circuit; and a work-circuit; a generator regulator; and means for automatically affecting the operation of the latter upon voltage changes; and means whereby the effect produced by said regulator will automatically increase the resistance of the generator circuit and control the condition of the battery circuit.

10. An electric system comprehending a generator and its circuit; a field-circuit; a battery and its circuit; and a work-circuit; a variable resistance in the field circuit for controlling the battery charging current; means connected across the generator circuit for preventing the battery from being

charged beyond a predetermined maximum; and means controlled by the last named means for adjusting the generator circuit and automatically determining when the battery circuit is to be put in operative relation to the work-circuit.

11. An electric system comprehending a generator and its circuit; a field-circuit; a battery and its circuit; and a work-circuit; a generator regulator; means for controlling the action thereof, so that the generator may properly charge the battery and supply the work-circuit; means for regulating the operation of said generator controlling means; and means governed by the effect of said last named means for automatically controlling the operative relation of the battery and the generator to the work-circuit, whereby the generator, the battery, or both, may supply the work-circuit.

12. An electric system comprehending a generator and a normally open circuit therefor; a battery and a normally closed circuit therefor; a work-circuit; a plurality of resistances in the generator circuit; and means for controlling the output of the generator operating to include both resistances when the generator and battery are together supplying the work-circuit, and cut out one of said resistances when the generator is supplying the work-circuit and charging the battery.

13. An electric system comprehending a generator, a storage battery, and translating devices, combined with means for regulating the generator responsive to variations in current; means for varying the action of said regulating means dependent upon battery conditions; controlling means for said varying means; and automatic means in the generator circuit for determining whether the translating devices shall be supplied by the battery or generator and the extent to which said devices shall be supplied by both.
